(57) **CLAIM**

The ornamental design for a feathered knife block, as shown and described.

DESCRIPTION

FIG. 1 is a left side view of the feathered knife block.

FIG. 2 is a back side view of the feathered knife block.

FIG. 3 is a right side view of the feathered knife block.

FIG. 4 is a front side view of the feathered knife block.

FIG. 5 is a left perspective view of the feathered knife block.

FIG. 6 is a left side view of another embodiment of the feathered knife block; and,

FIG. 7 is a left side view of yet another embodiment of the feathered knife block.

The broken lines in the figures are for environmental purpose only and form no part of the claimed design.

The embodiments of FIGS. 6 and 7 are shown in single views, where the only differences between these embodiments and the first (FIGS. 1-5) are in the number of segments (seven in FIG. 6, five in FIG. 7, as compared to six in FIGS. 1-5), it being understood that all other surfaces are the same as those of the first embodiment.
